A. ROSNER

TRIP LEVER FOR OSCILLATING MAGNETOS

Filed Jan. 18, 1922

INVENTOR
ADOLPH ROSNER.

BY

Adolph Rosner
ATTORNEY

UNITED STATES PATENT OFFICE.

ADOLPH ROSNER, OF SPRINGFIELD, MASSACHUSETTS, ASSIGNOR TO AMERICAN BOSCH MAGNETO CORPORATION, OF SPRINGFIELD, MASSACHUSETTS, A CORPORATION OF NEW YORK.

TRIP LEVER FOR OSCILLATING MAGNETOES.

Application filed January 18, 1922. Serial No. 530,142.

To all whom it may concern:

Be it known that I, ADOLPH ROSNER, a citizen of the United States, residing at Springfield, in the county of Hampden, State of Massachusetts, have invented certain new and useful Improvements in Trip Levers for Oscillating Magnetoess; and I do hereby declare the following to be a full, clear, and exact description of the invention, such as will enable others skilled in the art to which it appertains to make and use the same.

The present invention relates to oscillating magnetoess for ignition systems of internal combustion engines, and particularly to the tripping mechanism thereof.

Heretofore, it was customary to machine the trip lever of the oscillating mechanism from a solid piece of metal, such as a drop forging, in order that it could withstand the heavy and frequent blows of the actuating pin carried by a moving part of the engine. The lever also was usually formed with a solid metal yoke which was keyed to the end of the oscillator shaft. In some cases the trip lever was formed of several laminations, yet it was no lighter in weight than the machined trip lever. This required mass and weight of the trip lever gave it considerable inertia, and owing to this inertia, the lever could not operate at very high speeds. When actuated or moved to cocking position by the actuating pin, or to normal position by the oscillating spring, the momentum of the lever would give it an overthrow at the end of the cocking movement or cause it to foul at the end of its oscillating movement. Fouling was caused by the actuator pin hitting the end of the lever before it had come to rest at normal position. The motion of the trip lever could not be quickly damped or brought to a rapid stop after oscillation. Its inertia further imposed great strains upon the bearings effecting undue wearing on the bearings.

In accordance with this part of my invention, I construct the trip lever from pressed-up sheet metal with web and flange portions, which are preferably respectively disposed transversely and axially of the axis of the oscillator, with the flange portion extending preferably axially from the web portion. The lever is connected to the os-

cillator, preferably by means of a hub member fastened to the oscillator, and the trip lever preferably comprises a member fastened to the oscillator, and a pressed-up sheet metal arm fastened, as by rivets, to such member. Springs also may be connected to the frame and such member for oscillating the oscillator and the lever.

With such construction, the trip lever is light in weight and, accordingly, can be more rapidly vibrated with less inertia and momentum than previous structures. By reason of such light weight, the lever will have less over-throw at the end of its cocking movement, will follow the actuating pin more closely during such movement, will become more rapidly damped and will not so readily foul at the end of its oscillating movement. Since the chance of fouling is reduced, a longer trip lever may be used with the effect that less strains are imposed upon the bearings and hence, greatly reducing the wear on the bearings. Moreover, such constructions may be made at less cost than machined, drop forgings or laminated structures.

In the accompanying drawing illustrating my invention in application, as an example, to an oscillating type of magneto:

Fig. 1 is a view in elevation of an end of a magneto employing my invention; Fig. 2 is a fragmentary sectional view of the trip lever and associated parts; Fig. 3 is an end view of the same and a striking pin, showing different positions of operation; and Figs. 4 and 5 are top plan and end views of the device as applied to an oscillating magneto having laterally extending oscillating springs.

Referring more particularly to the illustrations upon the drawing, the invention is shown applied to a magneto 1 having a frame 2 carrying a U-shaped magnet 3 fastened thereto by means of screws 4. To the end of the frame 2 is formed an integral extension 5 to which is secured, in any suitable manner, an oscillating spring housing 6 comprising an outer cylindrical member 7 and an inner similar member 8 telescoping with the member 7. The extension 5 has an upwardly extending portion 9 to which is fastened, by means of screws 10, a collector brush holder 11, a binding post button 12 surmounting this holder. Within

the magneto is rotatably supported an armature having a shaft, the end portion 13 of which extends through the housing 6 and is tapered to receive a hub member 14 held to the tapered portion 13 by a Woodruff key 15, the hub member 14 being held in axial position by a nut 16 and lock washer 17 connected to the threaded end of the shaft. The hub member 14 has a radial 10 extending portion 18 which is flat and substantially circular. This portion 18 has secured to it the member 8, and also a trip lever 19, by means of rivets 20, these rivets extending through apertures formed in the member 18 and beaded at both ends to secure the members 8 and 19 on opposite sides of the portion 18 of the hub member 14.

The member 8 is in the form of an annular channel, and, together with the member 7, 20 forms a housing for oscillating springs 21, which may be of any suitable form, such as spiral or concentric members. The trip lever is constructed of pressed-up sheet steel and comprises a web portion 22 extending 25 transversely of the shaft of the armature, and a flanged portion 23 extending from this web portion, axially of the shaft of the armature. The web portion 22 is of substantially circular form, but has a depending 30 extension 24 of triangular form which, together with the lower extending portions 25 of the flange 23, form the depending arm of the trip lever. The arm extends downwardly in the path of an actuating pin 26 carried by a moving or rotating part of the 35 engine upon which the magneto is installed and to which it furnishes ignition. In Fig. 3 of the drawing, the actuating pin 26 is shown, in full lines, in the position of initial contact with the arm of the trip lever, and in dotted lines, at substantially the final position of contact with said arm. The dotted line position of the arm, as shown in Fig. 3, is the position usually referred to as 40 a cocking position, after which, when the pin releases the arm, the springs will oscillate the trip lever, as well as the armature, to its original position, such as that shown in full lines in Fig. 3 of the drawing, where 45 it is again ready for its next actuation by the pin 26.

In Figs. 4 and 5 is shown a similar magneto carrying laterally extending springs 27 supported upon lugs 28 formed integrally with a bracket 29 secured, in any suitable manner, to the end of the magneto. These springs are of helical form and have their outer ends hooked over rollers 30 rotatably supported upon pins 31 secured to the outer 50 ends of the lugs 28, and have their inner ends hooked over rollers 32 rotatably supported upon pins 33 fastened to the lug portions 34 formed integral with the disc member 18 of the hub member 14. In other respects the 55 trip lever is constructed exactly the same as

in the illustrations shown in Figs. 1 and 2 of the drawing. When the trip lever is deflected, the pins 33 and the rollers 32 receive an angular movement effecting a tension upon the springs 27 until the lever has reached cocking position. It then is released by the actuating pin 26, and the springs 27 immediately act to return the trip lever, and the parts connected thereto, such as the oscillator, to its original position, such as that shown in full lines upon Fig. 5 of the drawing. Thus, during this oscillation of the armature, the interrupter of the magneto is operated and a spark is produced for ignition purposes. 60

Having thus described my invention what I claim is:

1. A magneto comprising a frame, an oscillator, a pressed-up sheet-metal trip lever connected to the said oscillator and comprising web and flange portions, and a spring operative to oscillate said oscillator. 85
2. A magneto comprising a frame, an oscillator, a pressed-up sheet-metal trip lever fastened to said oscillator and comprising a web portion disposed transversely to the axis of said oscillator and a flange portion extending from said web portion axially of said oscillator, and a spring operative to oscillate said oscillator. 90
3. A magneto comprising a frame, an oscillator, a trip lever comprising a member fastened to said oscillator and a pressed-up sheet-metal arm fastened to said member and having web and flange portions, and a spring operative to oscillate said oscillator. 95
4. A magneto comprising a frame, an oscillator having a shaft, a trip lever comprising a hub member fastened to said shaft and a pressed-up sheet-metal arm comprising a web and flange portions, rivets fastening the web portion of said arm to said hub member, and a spring operative to oscillate said oscillator. 100
5. A magneto comprising a frame, an oscillator, a trip lever comprising a member fastened to said oscillator and a pressed-up sheet-metal arm having web and flange portions, rivets fastening said arm to said member, and a spring operative to oscillate said oscillator. 110
6. A magneto comprising a frame, an oscillator, a pressed-up sheet-metal trip lever connected to said oscillator and comprising web and flange portions, and springs connected to said lever and said frame and operative to oscillate said oscillator. 120
7. A magneto comprising a frame, an oscillator, a trip lever comprising a member fastened to said oscillator and a pressed-up sheet-metal arm fastened to said member and comprising web and flange portions, and springs connected to said frame and said member and operative to oscillate said oscillator. 125

8. A magneto comprising a frame, an oscillator, a pressed-up sheet metal trip lever comprising a hub member fastened to said oscillator and an arm fastened to said hub member, rivets fastening said arm to said hub member, said arm comprising a web portion disposed transversely of the axis of

said oscillator, and a flanged portion extending from said web portion axially of said oscillator, and springs connected to 10 said frame and said hub member and operative to oscillate said oscillator and trip lever.

In testimony whereof I affix my signature.

ADOLPH ROSNER.
